US00D607427S

(12) **United States Design Patent**
Ho et al.

(10) **Patent No.:** **US D607,427 S**
(45) **Date of Patent:** **** Jan. 5, 2010**

(54) **HANDHELD ELECTRONIC DEVICE**

(75) Inventors: **Po-Lin Ho**, Taoyuan County (TW);
Yen-Hung Lin, Taoyuan County (TW);
Feng-Chen Chang, Taoyuan County (TW)

(73) Assignee: **HTC Corporation**, Taoyuan (TW)

(**) Term: **14 Years**

(21) Appl. No.: **29/323,429**

(22) Filed: **Aug. 26, 2008**

(51) **LOC (9) Cl. 14-03**

(52) **U.S. Cl. .... D14/138 AD; D14/138 AA;
D14/341**

(58) **Field of Classification Search** D14/137,
D14/138 R, 138 AA, 138 AB, 138 AC, 138 AD,
D14/138 C, 138 G, 147, 191, 203.1–203.8,
D14/218, 244, 247–248, 341–347, 432, 439,
D14/455–456, 496; D10/65, 78, 104; D13/168;
D18/7; 455/556.1, 566, 575.1, 575.3; 345/169

See application file for complete search history.

(57) **CLAIM**

The ornamental design for a handheld electronic device, as shown and described.

DESCRIPTION

FIG. 1 is a perspective view of a handheld electronic device showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines immediately adjacent the claimed areas, which encompass non-shaded regions, represent the bounds of the claimed design, while all other broken lines are directed to environment and are for illustrative purposes only; the broken lines form no part of the claimed design. The interior surfaces on the rear side of the front panel forms no part of the claimed design.

1 Claim, 5 Drawing Sheets
